APPARATUS FOR TREATING FLOUR AND
THE LIKE

Edwin F. Anderson, Buffalo, N. Y., assignor to
Pillsbury Flour Mills Company, Minneapolis,
Minn., a corporation of Minnesota

Application May 31, 1934, Serial No. 728,260

3 Claims. (CL. 259—2)

This invention relates to the treating of granular or pulverized material with a fluid medium, such as a gas or other fluid discharged under pressure. While the invention has wide general application, it is particularly well adapted for treating finely ground material, such as flour, to bleach or otherwise condition the same.

It is an object of my invention to provide highly efficient apparatus of the type above described which, through agitation, diffusion and deflection, causes finely divided material to form a cloud or shower within a treating chamber and which subjects the divided particles forming such cloud or shower to the action of a discharged gas or other fluid within that chamber.

It is a further object to provide treating apparatus of the class described wherein a stream of finely divided material such as flour is continuously disseminated and deflected within a treating chamber by a combined shaking action of the chamber itself and relative movement of a series of deflection elements disposed in said chamber.

Another object is the provision of treating apparatus of the class described wherein a cloud or shower of diffused particles is continuously produced and caused to move slowly in one general direction and wherein a gaseous or other fluid medium is introduced in said cloud or shower and also caused to move in a given direction and wherein the structure is such that the entire interior of the treating chamber, including all deflection elements, walls, etc., may be constructed, if desired, of wood or other material which are non-corrosive and cannot contaminate or injure edible material, such as flour and the like.

Still another object is the provision of a simple and efficient continuous process for treating granular or pulverized material, such as flour and the like, with a gaseous or other fluid medium which comprises first thoroughly diffusing and deflecting a stream of the material to set up a cloud or shower or particles moving in one direction and subjecting the particles in their diffused state to the action of a gaseous or other fluid medium which permeates the treating chamber.

These and other objects and advantages of the invention will be more fully set forth in the following description made in connection with the accompanying drawing, in which like reference characters refer to similar parts throughout the several views, and in which:—

Fig. 1 is a front elevation of an embodiment of my improved treating apparatus;

Fig. 2 is a vertical section taken on the line 2—2 of Fig. 4;

Fig. 3 is a vertical section taken on the line 3—3 of Fig. 1;

Fig. 4 is a top plan view of the apparatus;

Fig. 5 is a cross section taken on the line 5—5 of Fig. 3;

Fig. 6 is a bottom plan view of the apparatus 10 with the flexible delivery conduit detached, and

Fig. 7 is a detail sectional view showing the manner in which the deflection rods are mounted for movement relative to the shaker casing.

In the form of the invention illustrated an 15 upstanding skeleton mounting frame is provided comprising the four posts 8 secured together by horizontal beams 9. An elongated box-like treating casing, indicated as an entirety by the letter C is mounted within the skeleton frame for re- 20 ciprocating or shaking movement. Casing C, as shown, comprises the four longitudinal members 10 interconnected and braced adjacent their ends by the stringer members 11, the side walls 12, the rear wall 13 and doors 14 which close the 25 front of the casing. Doors 14 are detachably secured in suitable seats provided by two of the longitudinal members 10 and the stringer members 11 and an intermediately disposed stringer 15. A top 16 covers the upper end of the casing 30 and is provided with an upstanding, inverted, funnel-shaped entrance throat 16a in open communication with the interior of the casing and which has mounted therein two or more spaced 35 dividing plates 17 of wedge shaped cross section, the edged ends thereof being disposed upwardly. The open end of entrance throat 16a as shown is connected with a flexible conduit 18 which receives granular or pulverized material from a 40 suitable source of supply.

The lower end of the casing C is defined by a delivery hopper 19 terminating in an annular attachment flange to which a flexible delivery conduit 20 is secured. A divider plate 21 of angular form traverses hopper 19 with its vertex dis- 45 posed upwardly.

Casing C is mounted in the frame for bodily swinging movement and to this end flexible and preferably resilient brackets 22 are connected at their lower ends with the upper ends of posts 50 10 in parallelogram relation and are connected at their upper ends to the top cross members of beams 9 of the frame. A second set of similar hanger brackets 23 connect the lower end of the casing with intermediate portions of the support. 55

ing frame, all of said hanger brackets 22 and 23 being in parallelogram arrangement to permit bodily shaking or reciprocating of casing C forwardly and rearwardly of the frame.

5 As shown, divider plates 17 at the entrance of the chamber and angular divider 21 in the delivery hopper extend from front to back of the casing.

Several series of horizontal deflecting and agitating rods extend between the side walls 12 of casing C. As shown, the uppermost series 24 are mounted and secured between spaced depending plates or boards 25 supported from the casing top 16, and said uppermost series are preferably arranged 10 in substantially triangular formation with the sides of the triangle diverging downwardly from the central portion of the inlet throat 16a. Below rods 24 is mounted a second series of deflecting and agitating rods 26 traversing the cross 15 sectional area of casing C and being arranged in vertically staggered columns. Rods 26 are slightly shorter than the distance between the side walls 12 of the casing and are mounted for restricted sliding movement between a pair of 20 vertical mounting boards or plates 27, spaced a short distance from the respective sides 12 of the casing. The mounting plates 27 are provided with apertures 27a for loosely receiving rods 26 with freedom for slidable and various lateral 25 movements of said rods.

As shown, two additional series of deflecting and agitating rods 28 and 29 respectively, are mounted below series 26, at the medial portion of the casing similar in structure and manner of 30 mounting to the first series 26 although, as shown, comprising fewer horizontal rows. The rods in series 28 and 29 are also vertically staggered and are mounted with freedom for limited horizontal 35 sliding movement and various lateral movements.

40 A lower series of horizontal deflecting and agitating rods 30 are mounted a short distance above discharge hopper 19 and traverse the cross sectional area of casing C and are arranged and mounted similarly to the series 26.

45 A gas or fluid distributing conduit 32 extends horizontally across the upper portion of casing C as shown disposed between rod series 24 and 26 and this conduit is provided with a plurality of spaced lateral discharge ports 32a. One end of distributing conduit 32 is closed while the other end is connected by a flexible coupling 33 with a source of gas or other fluid under pressure.

50 Suitable means are provided for rapidly and swingably reciprocating casing C from front to rear and vice versa of the frame. As shown, said means comprises an eccentrically mounted wheel or disk 34 having peripheral engagement with an idler wheel 35 axially mounted in suitable bearing 35a secured to the rear of the casing. Eccentric wheel 34 is driven by suitable means 55 such as a motor 36.

60 Casing C, of course, defines a treating chamber and its structure is such that its entire interior and all elements mounted therein may be constructed of wood, fibre or other non-corrosive 65 material which will assure maximum cleanliness and obviate contamination of flour or other finely divided or granular edible material.

Rods 26, 28, 29 and 30 are preferably of circular cross section with smooth peripheral surfaces.

Operation

70 Finely divided or pulverized material, such as flour, is continuously fed into the top of treating chamber C through the entrance throat 16a.

Casing C is bodily shaken or reciprocated by the eccentric wheel 34, the resiliency of the hanger brackets 22 and 23 urging the idler wheel 35 against the eccentric at all times. The several sets of deflecting and agitating rods it will be noted are disposed transversely to the direction of shaking movement of the casing. In the shaking action of the casing the rods 26, 28, 29 and 30, because of their inertia, shift about sometimes moving longitudinally short distances, sometimes shifting laterally in different directions and sometimes turning slightly in their mounting plates due to the fact that the apertures accommodating the rods are of larger size than the cross sectional area of the rods. Flour or other divided material, of course, moves downwardly by gravity and is disseminated and deflected by striking the rods and by the bodily shaking action of the casing and the rods mounted therein and by the relative shifting movements of the rods.

20 The combined shaking, deflecting and diffusing actions above described cause the flour or other finely divided material fed into the top of casing C to form a cloud or shower of diffused particles throughout the entire treating chamber.

25 Into this shower or cloud is discharged a gas or if desired, finely atomized jets of liquid under pressure and the fluid medium commingles and is agitated with the cloud or shower of diffused particles thereby efficiently contacting and thoroughly treating the same.

30 In the embodiment shown the discharge conduit 32 is disposed at the upper end of the chamber for distributing the fluid medium heavier than air which will consequently travel downwardly with the movement of the cloud of flour or other material treated.

35 In bleaching flour either the "Agene" or "Alsop" gas processes are usually utilized and in each instance the gas is heavier than air and is consequently introduced at the top. The gas acts chemically on the yellow carotin of the flour and in doing so decomposes. Treated material eventually falls slowly into the discharge hopper 19 and is discharged through the conduit 20.

40 In the above described operation flexible conduits 18, 20 and 33 permit bodily shaking of the casing without disturbing the several connections.

45 From the foregoing description it will be seen that due to the combined shaking and agitating movements of the casing and the several series of rods which are arranged in staggered relation, a very thorough diffusion or dissemination of the materials introduced is effected and the gas or other fluid is discharged into the material in the 50 most efficient manner.

55 With my improved structure it is impossible for finely divided material, such as flour or the like, to lodge at any point within the treating chamber, since the walls of the treating chamber C are smoothly finished on their interior as well as the surfaces of the several mounting plates for the deflecting and agitating rods and further since the rods are shiftable longitudinally, laterally and through oscillation and have smooth cylindrical peripheral surfaces. By obviating the lodging of material treated, all material is subjected to treatment for approximately the same period of time and no material will be 60 spoiled because of over-treatment.

65 The structure of my device including the doors 14 enables the treating chamber and all elements therein to be easily and frequently cleaned.

70 Extensive actual use has shown the method 75

and apparatus to be productive of highly efficient results.

It will, of course, be understood that various changes may be made in the form, details, proportions and arrangement of the parts, without departing from the scope of my invention, which, generally stated, consists in a device capable of carrying out the objects above set forth, and the novel parts and combinations of parts disclosed and defined in the appended claims.

What is claimed is:—

1. In apparatus for treating finely divided material, an upright casing defining a treating chamber having smooth interior walls, said casing having a material inlet at one end thereof and a material discharge at the opposite end thereof, means for bodily shaking said casing, and a series of diffusing and deflecting rods traversing the interior of said casing and mounted for shifting movement relative to said casing and shifted by the bodily shaking movement of said casing, said rods having smooth rounded peripheral surfaces and being mounted in smooth mounting plates whereby through the bodily shaking of said casing and the relative movement of said rods no material will lodge within said treating chamber.

2. In treating apparatus of the class described, a casing defining a treating chamber, said casing having a material inlet adjacent one end thereof and a material discharge adjacent the opposite end thereof, means for bodily shaking said casing and a series of diffusing, deflecting elements mounted for limited shifting movement throughout the cross sectional area of said chamber and means for mounting said elements whereby they are shifted by the bodily shaking movement of said casing, wherein said elements comprise rods loosely mounted for limited lateral shifting relative to said casing.

3. In treating apparatus of the class described, a casing defining a treating chamber, said casing having a material inlet adjacent one end thereof and a material discharge adjacent the opposite end thereof, means for bodily shaking said casing and a series of diffusing, deflecting elements mounted for limited shifting movement throughout the cross sectional area of said chamber and means for mounting said elements whereby they are shifted by the bodily shaking movement of said casing, wherein said elements comprise rods loosely mounted for limited lateral shifting and oscillation relative to said casing.
